SOFT X-RAY TUBE

Charles M. Slack, Bloomfield, N. J., assignor to
Westinghouse Lamp Company, a corporation
of Pennsylvania

Application January 9, 1930. Serial No. 419,479

1 Claim. (Cl. 250—35)

The present invention relates to devices employed in the production of X-rays of long wave length, usually termed soft X-rays or Grenz rays, and particularly to the production of X-rays of from 2 to 8 angstroms in wave length.

For certain medical purposes it is desirable to produce soft X-rays since these have a low penetrating power. Hard X-ray tubes are not suitable for these purposes since the short wave length rays penetrate too deeply and very few are absorbed by superficial parts of the body treated.

Within an X-ray tube of the hot cathode, high vacuum type the hardness of the rays produced depends on the impressed voltage. By impressing less than ten kilovolts upon the tube only the soft X-rays will be produced therein. The glass walls of conventional X-ray tubes, however, are so thick that they absorb practically all of the soft X-rays produced.

Soft X-ray tubes have been provided with windows of various materials, such as aluminium foil and Lindemann glass for the projection of soft X-rays into the open air. Wehnelt and Trenkle in publication entitled "The Production of Very Soft Roentgen Rays" appearing in the Erlanger Physical Institute of the University November, 1905, described a vacuum tube of the hot cathode type having an aluminium foil window attached thereto, which tube was capable of projecting soft X-rays through the window when the tube was operated with an impressed potential difference of about 7,000 volts. Lindemann glass windows for soft X-ray tubes have been proposed in Bucky Patents 1,679,332, 1,679,394 and 1,708,494 issued July 31, 1928, August 7, 1928 and April 9, 1929.

Aluminium foil of a thinness of 0.004 m. m. or about 0.00015 inches such as employed by Wehnelt and Trenkle is extremely fragile and if of any appreciable area, it must be supported by a heavier metal structure to which it must be secured in a gas tight manner. The metallic structure, in turn, must also be sealed to the glass portion of the envelope in a gas tight manner. This construction is both costly and difficult to effect. Difficulty is also experienced in degassing the metal parts within the tube without destroying the window. Lindemann glass windows present the disadvantage that due to the brittleness of this material a window capable of withstanding atmospheric pressure is limited in thickness to a minimum of about 0.008 inches at which thickness a major portion of the rays of 3 angstrom wave length are absorbed by the window. From a manufacturing standpoint Linde-

mann glass presents a further disadvantage in that it is difficult to effect a good seal between a thin film of this material and the ordinary glass portions of a tube.

Another disadvantage of Lindemann glass is that it deteriorates on exposure to atmosphere and must be coated with some such material as shellac or lacquer to protect it. This coating must be renewed frequently or the rays themselves disintegrate the coating material.

One of the objects of my invention is to provide an improved "window" for a soft X-ray tube which will project a major portion of the X-rays produced through the same.

Another object of my invention is to overcome the difficulties inherent in the windows in use at the present time and to employ a portion of the glass envelope of the device through which soft X-rays may be projected.

A still further object is to produce a "window" for a soft X-ray tube which may be made extremely thin while retaining sufficient strength to resist the external atmospheric pressure and which will absorb but a very small proportion of the soft X-rays produced in the tube.

According to my invention I provide a window permeable to soft X-rays and composed of glass or other vitreous material of extreme thinness such as the one described in my Patent 1,735,302 issued November 12, 1929.

Briefly this window consists in an indrawn bulbous portion on the end of the tube of a thickness of from 0.0001 to .005 inches.

For the purposes of the present invention the thickness should be less than 2 mils since with a wave length of 2 angstroms, the most penetrating of those considered, a window 10 mils thick will transmit less than one part in a thousand of the radiations, a window 5 mils thick will transmit less than one percent, a 2 mil window will transmit 14 percent, a 1 mil window 40 percent, and a 0.1 mil window will transmit about 90 percent.

At a wave length of 3 angstroms 1 mil of glass will transmit about 5 percent of the radiations, 0.1 mil about 80 percent and 0.04 mils about 90 percent of the radiations.

In order that the invention may be more fully understood, reference will be had to the accompanying drawings in which;

Fig. 1 is a central sectional view of a soft X-ray tube constructed in accordance with my invention, and

Figs. 2 and 3 are similar views on an enlarged

scale disclosing other embodiments of my invention.

The tube shown in Fig. 1 comprises a glass envelope 1 having a relatively heavy wall and containing a filamentary cathode 2 and an anode 3. The anode supporting end 4 of the tube has a reentrant glass stem 5 terminating in a press 6 through which a leading in conductor 7 for the anode is sealed.

10 The envelope 1 may be composed of any suitable glass, such as ordinary lime glass, pyrex or a glass which is less opaque to X-rays.

The cathode 2 may be of any suitable electron emitting material, but I prefer to construct it 15 of tungsten or tantalum in the form of coil 8 mounted within a focusing cup 9 as is usual in X-ray tube construction. The focusing cup 9 is supported by leading-in and supporting conductors 10 which are sealed in the press 12 of an 20 outwardly projecting stem 11 located at the side of the tube adjacent the end 13 which is opposite the anode supporting end 4.

The end 13 of the tube may be enlarged and the window 14 formed therein. In forming 25 window 14 the enlarged end is heated by a blow pipe flame or other suitable heating means and a suction created on the interior thereof so that the plastic glass is drawn in, the heating and suction being continued until the requisite size 30 and thickness of the bulbous portion of the tube is obtained. The window 14 may preferably have a thickness of from 0.00004 to 0.002 inches. By properly controlling the application of heat 35 a considerable area of the central portion of the window may be drawn very thin and have a substantially uniform thickness, the walls gradually increasing in thickness from the central portion to the outer edge of the bulbous portions.

40 The leading in and supporting conductors 10 may be offset as shown at 15 so as to dispose the cathode 2 in close proximity to the window 14 and at the same time incline the focusing cup 9 away from the window so that cathode rays emerging from the filament 8 cannot strike the window, the filament being withdrawn into the focusing cup 9 to effect this result. The focusing cup 9 directs cathode rays to the center of a target 16 of tungsten or thorium or other 45 suitable material secured to the anode 3 thru the intermediary of a bonding disc 17 which may be of tantalum, molybdenum or tungsten.

The anode 3 is preferably composed of copper 50 and supported by a sleeve 18 at the end 4 of envelope 1. To dissipate the heat produced by the bombardment of the anode it is made heavy and rather long as illustrated. For large energy dissipations a radiator or water cooling device may be added in a manner well understood in the 55 art.

For the purpose of spreading the rays over a large area the window 14 is made shallow and has a wide mouth. The electrodes are also disposed closely adjacent the window so that the 60 cone of rays emitted by the tube form a large solid angle.

Referring to Fig. 2 of the drawings there is 65 illustrated a soft X-ray tube embodying my invention and particularly designated for treatment of the mouth and throat. This embodiment comprises a glass envelope 20 of cylindrical shape and contains a cylindrical glass tube 21 supported at one end in the envelope 20 by a sleeve 22.

70 The free end of tube 21 supports on its ex-

terior a cup shaped metal shield 23, said shield 23 having a central aperture 24 in the end wall thereof. The free end of tube 21 also supports a sleeve 25 of insulating material on its interior, said sleeve having a pair of oppositely disposed longitudinal grooves 26 cut along its interior surface which serve frictionally to support a cathode in the form of a filament coil 27 which is slightly larger in diameter than the aperture 24.

75 Leading-in conductors 28 for the coil 27 pass through apertures 29 in the end wall of shield 23 and emerge from the envelope 20 at about the central portion thereof to join suitable terminals 30. An anode 31 is centrally supported within the tube 21 by a sleeve 32 and a leading-in conductor 33 for the anode 31 is sealed in the press 35 of a reentrant stem 34 in the same manner as previously described relative to elements 5, 6, 7 of Fig. 1.

80 A thin window 36 similar to window 14 of Fig. 1 is formed in the end of the envelope 20 opposite the anode supporting end and in alignment with the aperture 24, a filament coil 27 and anode 31. The terminals 30 are disposed remote 90 from said window to permit insertion of the window 36 and the portion of the envelope supporting the window into the mouth.

95 In Fig. 3 another embodiment of my invention designed particularly for treatment of small 100 areas such as those within the nose or ear is illustrated. This tube may be constructed in essentially the same manner as the tube shown in Fig. 2 except for the window structure which comprises a small thin window 36' formed in a 110 tube 37 of about a half inch or less in diameter. Preferably the window 36' is formed on a piece of glass tube 37 and the tube subsequently fused to an envelope 20'.

115 In the above described devices the electrodes should be thoroughly degasified in accordance with the practice followed in the construction of X-ray tubes. Prior to assembly the metal parts are heated to a red heat to remove the major portion of the occluded gases and after assembly the electrodes and associated parts are sealed into the envelope, a high vacuum created and the final degasification effected by electronic bombardment and high frequency induction heating while the tube is on the exhaust pumps. 120 After the final degasification the tube may be sealed off from the pumps and constant operating conditions may be obtained when the tube is worked at the potential necessary for the production of soft X-rays. If desired, a small pressure of from 1 to 10 microns of a monatomic gas, 125 such as neon may be admitted to the envelope. In either case the arrangement of the electrodes and gas pressures employed are such that the device may be operated to produce X-rays in the 130 absence of detrimental gaseous ionization.

135 In operation when a small potential difference is impressed on the cathode leading-in wires and a desired potential difference impressed on the anode and cathode leading in conductors X-rays 140 of a known minimum wave length will be produced within the tube. An extremely thin window will absorb but a very few of the longer wave length X-rays so that the major portion of the soft rays are available for treatment purposes. The thicker the window is the greater the 145 number of the softer rays which will be absorbed by the window and the smaller the efficiency of the tube. As the potential differences impressed on the anode and cathode are in- 150

creased the minimum wave lengths of the radiations produced are decreased and a greater proportion of the hard penetrating rays are produced.

5 If, for example, radiations in the region of 2 to 4 angstroms wave length are desired a potential difference of 6 kilivolts may be impressed on the anode and cathode and by using a window of 10 0.00004 inches thickness about ninety percent of these radiations produced will pass through the window. If radiations of a minimum wave 15 length of 8 angstroms are desired about 1.5 kilivolts potential difference is impressed on the electrodes. With the same window a lower percentage of the rays will be emitted by the tube. I have found that the windows having silicon as 20 the predominating element offer the greatest resistance to the passage of X-rays in the neighborhood of 7 angstroms wave length, and at about that point the absorption coefficient drops so that for 8, 9, 10, 11 and 12 angstroms more of the rays will pass through the window than will at 7 angstroms.

It is to be understood that although my tube

25

is particularly designed for the production of X-rays of from 2 to 8 angstroms, it is capable of transmitting radiations of a greater wave length, such as those from 8 to 15 angstroms.

What I claim is:

An X-ray tube comprising an envelope of cylindrical form, a cathode and an anode within said envelope, leading-in conductors for said anode and cathode, the leading-in conductor for said anode extending through one end of the envelope 80 and the leading-in conductors for said cathode extending from the sides of the envelope at diametrically opposed points, said envelope comprising a body portion containing an element 85 whose atomic weight is greater than 16 and a window at the end of said envelope and of substantially the same composition as said body portion, said window being homogeneously united to said body portion and having a portion thereof of not greater than 0.002 inches in thickness, said leading-in conductors emerging from the envelope 90 at points remote from the window.
